LOCK FOR A MACHINE

Anthony B. Bennett, 25 E. 86th St., New York, N.Y.
10028, and Max Steinberg, 18 Jeffery Lane, Lake
Success, N.Y. 11040

Filed Apr. 25, 1967, Ser. No. 6,842

Term of patent 14 years

(Cl. D50—7)

FIG. 1

FIG. 2

FIG. 3

FIG. 4

FIG. 5

FIG. 6

FIGURE 1 is an elevational view of a lock for a machine showing our new design;

FIGURE 2 is an end elevational view thereof;

FIGURE 3 is an elevational view of the other end thereof;

FIGURE 4 is a top plan view thereof;

FIGURE 5 is a side elevational view thereof; and

FIGURE 6 is a bottom plan view thereof.

The dominant portion of our design resides in those portions shown in full lines.

The broken lines in FIG. 1 showing a portion of a table top and a machine thereabove are for illustrative purposes only.

We claim:

The ornamental design for a lock for a machine, as shown and described.
